UNITED STATES PATENT OFFICE.

MILTON MYERS, OF PHILADELPHIA, PENNSYLVANIA.

DESIGN FOR A BOTTLE-WASHING BRUSH.

48,756.

Specification for Design.

Patented Mar. 21, 1916.

Application filed November 22, 1915. Serial No. 62,926. Term of patent 3½ years.

To all whom it may concern:

Be it known that I, MILTON MYERS, a citizen of the United States, residing in the city and county of Philadelphia, State of Pennsylvania, have invented a new, original, and ornamental Design for Bottle-Washing Brushes, of which the following is a specification, reference being had to the accompanying drawing, forming part thereof.

Figures 1 and 2 are elevations, respec-

tively, at a right angle to each other of a bottle-washing brush, showing my new design.

I claim:—

The ornamental design for a bottle-washing brush as shown.

MILTON MYERS.
